UNITED STATES PATENT OFFICE

162,861

PULL MEMBER FOR ROLLER CURTAINS OR THE LIKE

Dayton J. Morehouse, Springfield, Mass.

Application August 24, 1949, Serial No. 4,672

Term of patent 7 years

(Cl. D10—8)

To all whom it may concern:

Be it known that I, Dayton J. Morehouse, a citizen of the United States, residing at Springfield, in the county of Hampden and Commonwealth of Massachusetts, have invented a new, original, and ornamental Design for a Pull Member for Roller Curtains or the like, of which the following is a specification, reference being had to the accompanying drawings, forming part hereof:

Fig. 1 is a plan view of a pull member for roller curtains or the like showing my new design;

Fig. 2 is a front elevational view of the pull member shown in Fig. 1;

Fig. 3 is a rear elevational view of the pull member shown in Figs. 1 and 2; and

Fig. 4 is a side elevational view of the same.

I claim:

The ornamental design for a pull member for roller curtains or the like, as shown.

DAYTON J. MOREHOUSE.
